UNITED STATES PATENT OFFICE.

JOHN ADDISON CLARK, OF BOLCKOW, MISSOURI.

BROODER.

1,081,811.

Specification of Letters Patent.

Patented Dec. 16, 1913.

Application filed April 2, 1912. Serial No. 687,959.

To all whom it may concern:

Be it known that I, JOHN ADDISON CLARK, a citizen of the United States, and a resident of Bolckow, in the county of Andrew and 5 State of Missouri, have invented a new and Improved Brooder, of which the following is a full, clear, and exact description.

My invention relates to an improvement in brooders, and it comprises a combined 10 brooder and coop construction which is so mounted as to be automatically actuated by the weight of the chicks it contains, to cause the same to close up and house and protect the chicks when a certain number of the 15 young fowls have entered the same. The capacity of the brooder can be adjusted to accommodate a greater or less number of chicks, and the operating parts can also be adjusted so as to require a greater or less 20 weight to cause the brooder to close and house the chicks and at the same time prevent any more from entering it. My brooder is given the shape which best adapts it to 25 serve these purposes, and the roof thereof is formed so as to prevent young chicks from obtaining a foot hold and thus roosting thereon for the night.

These and other features of construction 30 will more fully appear from the following description and drawings accompanying the same, and be particularly pointed out in the claims appended thereto.

Reference is to be had to the accompanying 35 drawings forming a part of this specification, in which the same characters of reference indicate the same parts in all the views.

Figure 1 is a perspective view of the front 40 of my improved brooder; Fig. 2 is a vertical longitudinal sectional view taken on the line 2—2 of Fig. 3; Fig. 3 is a top plan, partly in section, showing the brooder with the cover or roof removed; Fig. 4 is a vertical section 45 through the top of the brooder on the line 4—4 of Fig. 3; Fig. 5 is a vertical sectional view through the adjacent edges of the body 50 of the brooder and the top or roof therefor, showing the manner in which the roof can be held in raised position; Fig. 6 is a view 55 of the lock, showing the same in position to hold the brooder closed; Fig. 7 is a vertical section taken through one side of the brooder, showing the catch for holding it 60 open until a sufficient number of chicks have 65 entered the same; and Fig. 8 is a detail view showing the stop which projects from the

bottom of the brooder to prevent the same from moving too far when the operating parts are actuated to close the same and house the chicks.

On the drawings the numeral 1 represents 60 a strip of wood which is secured to a similar transverse strip 2, these strips or sticks being secured together at the middle by recessing the same, as shown in Fig. 2, and serving as 65 a base or foundation for the brooder. 3 is a curved platform, preferably in two parts secured to the opposite ends of the strip 1, and one of the ends of the strip 2, this platform having the form shown in Fig. 3, and 70 the widest portion containing the corner being so located as to be directly opposite the doorway to the inside of the brooder when the brooder is open. The platform 3 has a piece of wood 4 on the under side of the 75 same which extends from the corner thereof opposite the doorway leading into the brooder to the point of intersection of the pieces of wood 1 and 2.

The base pieces 1 and 2 support a stand- 80 ard 5, which may be in the form of a piece of gas pipe or similar tubing which is rigidly secured to the foundation strips, as required. This standard 5 supports a block 6, which is so mounted thereon as to be held 85 against rotation. For this purpose I preferably perforate the standard 5 and pass a pin shown at 6' in Fig. 2, through this perforation. The block 6 will be formed with a groove in its under side which receives the 90 pin 6', and this pin 6' will therefore hold the block 6 and prevent it from slipping around on the standard. The standard may likewise be perforated adjacent its upper end to receive a pin 5', the object of this pin 95 being to prevent the cover, which will be referred to later, from being removed or blown off by the wind.

To the block 6 are secured a number of 100 eyelets 7, and to these eyelets are attached the upper ends of a number of springs 8. The lower ends of these springs are secured 105 to hooks fastened to a trough-shaped member 9. This trough-shaped member 9 consists of a pair of sides 10, the lower edges of which are joined adjacent the ends by means of bottom pieces of metal or wood, shown at 11, the space between these bottom pieces 11 permitting the standard 5 to pass through. The trough 9 serves as a suspension for a 110 cross-beam 12, as is shown in Figs. 2, 3 and 4, this cross-beam 12 being rigidly secured

at its opposite ends to the body 13 of the brooder, this body being made of strips of tin or other metal bent in the form shown and closed by means of a suitable bottom, 5 shown at 14. The side of the body 13 has a doorway or entrance 15 cut therethrough, and the lateral edges of this doorway are bent inward, as shown at 16, and these inward portions 16 are perforated as shown 10 at 16'.

The object of the perforations 16' is to enable the size of the opening to be increased or decreased at will. This is accomplished by means of rods or wires which are passed 15 through the perforations 16'; and it will be obvious that if a single wire be passed through the uppermost pair of apertures 16' on either side of the doorway, the size of this doorway will be decreased to a certain 20 extent. If more than a single wire be employed, the size of this doorway will be still further decreased, and, thus, only chicks of a certain size will be permitted to enter. As the chicks grow, these wires may be removed 25 so as to increase the size of the doorway to the extent required. The wire rods or the like which may be employed to decrease the size of the doorway 15 in this manner are shown at 44 in Fig. 2, the cross-beam 12 having notches 12' in its ends to receive them. The wire rods are kept in this 30 position when they are not needed.

The cross-beam 12 has a pair of adjustable threaded bolts 17 passing through the 35 same on either side of the standard 5. These bolts have wing-heads at their upper ends so that they can be adjusted by means of the fingers of the attendant, and they pass through the cross-beam 12 to engage the bottom pieces 11 of the trough 9. The cross-beam is also provided with apertures 18 which pass through the same from one side to the other on either side of the standard 40 5; and these openings 18 can be made to serve the same purpose as the bolt 17, by 45 passing pins shown at 18' in Fig. 4, therethrough; that is to say, they can cause the beam 12 to be suspended high or low in the trough 9, as conditions may require.

The roof or cover for the brooder is shown 50 at 19, and this cover is made conical to prevent the chicks from finding a foot hold on the outside of the same and roosting thereon. From the inside surface projects a stop 55 20, which extends down below the top of the cross-beam 12 and limits the rotation of the cover 19 with respect to the top; and 21 is an eyelet or finger hold on the outside of the roof to permit the same to be manipulated. The top of the body of the brooder 60 and the bottom edge of the cover 19 are provided with wire ribs 22 and 23, respectively, to strengthen the same, as shown, the edges being crimped over the wires to hold them 65 in place. The inner side of the body is also

provided adjacent its upper edge with a plurality of pivoted blocks 24. The object of these blocks is to permit the cover to be raised to provide a space between the upper edge of the body 13 and the roof or cover for 70 purposes of ventilation; and when the blocks 24 are turned to vertical position this effect is produced. When they are turned to lie in horizontal position, as shown in Fig. 3, the cover will rest upon the top of the body 75 and close the same.

The numeral 25 represents a curved plate which is secured to the inner curved edge of the platform 3, and secured to one edge of this plate 25 is a curved sheet of foraminous material 26, which is bent away from the inner edge of the platform 3 at its outer end, as shown in Figs. 1 and 3 of the drawing. The adjacent edges of the plate 25 and the sheet of foraminous material 26 are secured 80 together and to a standard 3' mounted upon the platform 3 to brace the same. Normally, when the brooder is closed, the doorway 15 will be located directly behind the foraminous material 25, to prevent the feathered 90 occupants from making their exit.

Adjacent the bent end of the foraminous sheet 26 is a standard 27, which is bent over toward the outer surface of the body 13 at 95 its top, and this bent end supports a coiled spring 28 secured thereto and to an eyelet in the platform 3, so as to be held in vertical position. This spring serves as the door guard and acts in a manner that will be explained later.

Pivoted to the outer face of the body 13 of the brooder at some distance from the doorway 15 and adjacent the bottom of the brooder is a wedge-shaped block 29, and located near this block 29 is a pin or projection 30, which extends outward from the curved side wall of the brooder. This pin engages a pivoted catch 31, which is allowed to swing in one direction, and is held against movement in the opposite direction by 100 means of a pin or stop 32, mounted on a block 33 carried by one end of the wooden strip 2.

34 represents a series of holes in the platform 3 adjacent the inner edge of the same; 115 and 35 is a pin or stop which fits into any one of these holes.

The numeral 36 represents a block having one end beveled, carried by the platform 3 above one end of the base piece 1, and normally located between the block 33 and the standard 27, the purpose of this block being 120 to hold the brooder in open position.

The numerals 37 represent a pair of bolts similar to the bolts 17, passing through 125 apertures in the end of the cross-beam 12, and having screw-threaded engagement adjacent their lower ends with a bar 38. To the sides of this bar are pivoted a pair of strips 39, and these strips support semi-cir- 130

- circular ribs fastened thereto at their opposite ends. Each of the bars 39 and ribs 40 thus forms a semi-circular frame which is covered by means of a web of fabric 41.
- 5 42 are strips of fabric which are arranged around the inside of the body of the brooder and have lugs 43 which engage the top edge of the body 13 and hold the fabric 42 in place.
- 10 45 represents flat strips or plates secured to the tops of the strips or bars 39 and extending under the lateral edges of the bar 38, the purpose of these plates 45 being to hold the semi-circular frames covered by the 15 fabric 41, in horizontal position, permitting them to be raised upward but preventing them from swinging downward beyond a certain point.
- In practice, the position of the cross-beam 20 12 with respect to the suspension trough 9 will be so adjusted as to cause the body 13 of the brooder to be retained at such a level that the pin or projection 30 will normally be above the lower end of the swinging arm 25 31. This can be effected either by means of the apertures 18 and the pins 18', or by turning the screws 17 which have screw-threaded engagement with the cross-beam 12. To open the brooder, one takes hold of 30 the eyelet 21 and turns the cover, and the projection 20 on the inside thereof will engage the beam 12 and turn the body 13 with it. This will move the doorway 15 from behind the plate 25 and foraminous sheet 26 35 to the position shown in Fig. 1, the pin or projection 30 passing by the swinging arm 31, and being held by the swinging arm against returning. When a sufficient number of young chicks pass inside the brooder 40 through the doorway 15 at night fall or at any other time, the body 13, which has no engagement with the standard 5 except through the springs 8, will be depressed against the tension of the springs 8, and as 45 a result the projection 30 will finally clear the lower end of the arm 31. This relative position of the parts is illustrated on Fig. 7. The action of the springs 8 will now cause the body 13 to swing to such an extent as to 50 carry the doorway 15 behind the plate 25 and close up the brooder; and it will be observed that when the brooder is swung to open position the lower ends of the springs 8 are caused to rotate to a certain extent 55 around the standard 5 to come into position to exert a returning force on the brooder when the same is released in the manner described. When the brooder swings shut, the block 29 will slide up over the top of the 60 stop 35. When it passes the stop the rear end of the block will drop down into contact with the platform 3, and this stop will then prevent the body of the brooder from moving to uncover the doorway 15. As a result, 65 the brooder will be closed up and the chicks housed and protected for the night. Whether the block 29 will hold the body with the doorway adjacent the foraminous member 26 or behind the solid plate 25, will depend upon the position of the stop 35, a 70 plurality of the holes 34 being provided to enable the position of the stop 35 to be adjusted. The stop 35 will further be employed to cause the doorway to be located behind the plate 25 when the brooder moves 75 after being released from the stop 31 to a greater or less extent, merely by providing a sufficient number of holes 34. For example, the pin may be set in such a way that the doorway will be partly closed by the plate 25 to any required extent, and the brooder protected against the intrusion of animals destructive to the poultry, by the interposition of the screen 26 over the remaining portion of the doorway. In this way the 80 occupants of the coop can be protected from harm, and all necessary ventilation readily secured.
- The object of the spring 28 is to prevent any chicks from being accidentally caught 85 between one edge of the doorway 15 and the edge of the foraminous sheet 26, and injured, if a chick should be in the act of trying to enter the brooder when it begins to close up. The effect of this door guard will 90 be to sweep aside any chick that might otherwise be caught between the end of the foraminous sheet 26 and one edge of the doorway 15, and push it into the brooder.
- In order to prevent the brooder from 95 swinging to such an extent as to cause a collision between the trailing block 29 and the door guard, I form a projection 46 on the bottom 14 of the brooder. This projection is located in such a position that it will strike 100 the foundation piece 1, but the trailing block 105 cannot strike the door guard 28. A notch is formed in the member 2 to permit the projection to pass.
- The extent of the doorway 15 can be regulated by means of rods passed through the apertures 16', so as to prevent chicks above a certain size from entering the same. Likewise, the weight required to cause the body 110 of the brooder to sink and make the projection 30 clear the lower end of the arm 31, can be controlled by adjusting the depth at which the cross-beam 12 is carried in the suspension trough 9. This can be effected by turning the screw 17 or by properly placing 115 the pins 18' in the apertures 18. If the means in question are manipulated so as to raise the beam 12 with respect to the trough 9, the effect of course will be to elevate the body 13 of the brooder and make it 120 necessary for a larger number of chicks to enter the same before the body will be depressed to such an extent as to release it. The screws 17 are preferably for close adjustment, but careless attendants will allow 125 130

them to become rusted, so that they will stick in their sockets and refuse to work. In this case the pins 18' can be used instead.

The purpose of the semi-circular frames 5 or wings which support the sheets of fabric 41, is to carry material to be placed thereon to absorb and retain the warmth generated by the chicks when huddled together in the brooder. The distance of the sheets of 10 fabric 41 above the bottom 14 of the brooder can be adjusted by means of the thumb-screws 37, according to the size of the chicks for which the brooder is used. The cloth or other fabric 42 will protect the chicks from 15 contact with the inner surface of the cold metal walls of the brooder, and fine chaff or other litter will be spread over the floor for the same purpose.

My improved brooder is positive in action, 20 being operated by gravity, and while it is not a weighing machine, it may be readily adjusted to act as such for all practical purposes in poultry raising. There are no angles on the inside of the same into which 25 the chicks may be crowded and smothered, and the shape of the roof is such that it does not afford any foot hold to enable the chicks to try to roost thereon, as above set forth, and thus a good deal of the nuisance 30 and vexation against which poultry raisers have to contend is eliminated. By means of the automatic action of the parts causing the brooder to close up when filled to a certain extent, danger of overcrowding and the 35 resultant weakening effect and liability to diseases are entirely obviated, and these results are, further, insured with no extra attention on the part of the attendant. These brooders will of course be used in groups, 40 and some of them can therefore be located to raise young chicks of one size and be operated when they are loaded up to a certain weight, and others be adjusted so that they will accommodate chickens of another size 45 and be operated to close when loaded up to another weight, so as to accommodate and take care of all grades and ages of young fowls; and should there be any in the poultry yard which do not get weighted up to 50 the closing point, by reason of the fact that the last ones that fill always take the overflow from the others, a slight pressure on the lid will press down the body and allow the brooder to close in the ordinary way.

55 The function of the button 36 is to enable the brooder to be kept in open position when for any reason it is not desired that the same can swing to closed position, and it is made effective by rotating it to bring its beveled 60 end beneath the bottom of the brooder. When the brooder is opened and the beveled end of the button 36 is turned to pass under the bottom thereof the structure will remain 65 in open position, regardless of the weight therein contained, until the said button is

turned aside. The cover or top 19 can be raised and held in raised position by the pivoted blocks 24, to supplement the ventilating effect of the doorway at such times. It is also to be noted that by regulating the 70 height to which the cross beam 12 is supported in the trough 9, the weight required to liberate the brooder and cause it to swing to closed position can be readily adjusted. This weight will be controlled so as to be 75 greater as the young chicks grow, and if at any time the brooder will not swing shut when all the occupants are housed within the same the poultryman can merely press down upon the top when making his rounds 80 in the evening, to release the pin 30 from the catch 32 and thus allow the parts to be swung to closed position.

I wish to have it understood that the above description and drawings disclose but 85 one embodiment of my invention, and that I desire the right to make such small changes as fall within the scope and spirit of my invention, and do not wish to be limited to the details thereof, except in so far as is indicated in the appended claims. 90

Having thus described my invention, I claim as new and desire to secure by Letters Patent:

1. In an improvement of the kind described, the combination of a hollow body having a doorway through the wall thereof, a standard passing through the bottom of said body, resilient means for suspending said body from said standard to enable the 95 same to rotate around said standard and be elevated or depressed with respect thereto, a projection mounted upon the outside of said body, a catch mounted upon a fixed support adjacent said body to be engaged by said projection, said catch permitting said projection to pass when the body is moved in one direction, but holding the same against movement in the opposite direction, and a fixed member mounted adjacent 100 said body in such position as to be spaced from the doorway to the interior of the same when the said projection engages said catch, whereby when the said body is weighted, depressing the projection below 105 the catch, the springs will cause the body to rotate around the axis to move the doorway opposite the fixed member and close the same. 110

2. In apparatus of the kind described, the 115 combination of a body having a doorway through the wall thereof, a standard upon which said body is mounted to rotate, resilient means connecting said body to said standard to support the same in suspended 120 position, a fixed member mounted adjacent said body, means for holding said body in position to keep said doorway separated from said fixed member, said means being 125 releasable when the said body is weighted 130

to depress the same, whereupon the said resilient means will swing the body around the axis to move the doorway behind the fixed member and close the doorway, and
5 means carried by said body to prevent the return movement thereof to reopen said doorway.

3. In an improvement of the kind described, the combination of a rotatable body
10 having a doorway through the wall thereof, a fixed member mounted adjacent said body, a sheet of foraminous material forming an extension of said fixed member, and pivoted means mounted adjacent the base of the
15 body and movable into engagement with said base to hold said body in position with the doorway behind said fixed member or behind the sheet of foraminous material aforesaid.

20 4. In an improvement of the kind described, the combination of a body having a transverse beam secured to the top thereof, a suspension trough receiving said beam, said beam having a plurality of apertures
25 therethrough from one side to the other to receive pins on which said beam is supported to regulate the depth to which said beam rests in said trough, and means for suspending said trough.

30 5. In an improvement of the kind described, the combination of a body, a transverse beam secured to the top of the body, a suspension trough receiving said beam, a pair of bolts having screw-threaded connection with said beam and passing therethrough to engage the bottom of the trough to regulate the depth to which said beam is received in said trough, and means for suspending said trough.

6. In an improvement of the kind de- 40 scribed, the combination of a pivotally-mounted body having a doorway through the wall thereof, a fixed member, means for moving said body to bring the doorway adjacent the fixed member and close the same, 45 and a resilient door guard located adjacent the edge of the fixed member in operative relation to the doorway when the body is moved to bring the doorway into closed position.

50 7. The combination of a base, a body carried thereby, means for mounting the body and the base to be relatively movable, a swinging arm supported by said base, means for preventing said arm from moving in one 55 direction, and a pin carried by the body to engage the arm to hold the body in a certain position, said body being depressible to release the same.

8. The combination of a base, a body, 60 means for mounting said body on said base to make the body movable with respect to the base, said base having a plurality of apertures adjacent the edge of the body, a pin to engage any one of said apertures, 65 and a swinging catch carried by the body, said catch permitting the body to move in one direction and engaging the pin to prevent the body from moving in the other direction.

70 In testimony whereof I have signed my name to this specification in the presence of two subscribing witnesses.

JOHN ADDISON CLARK.
